UNITED STATES PATENT OFFICE.

THOMAS J. FAY, OF BROOKLYN, NEW YORK, ASSIGNOR TO THE GOBY ENGINE COMPANY, A CORPORATION OF OHIO.

INTERNAL-COMBUSTION ENGINE.

1,112,530.

Specification of Letters Patent.

Patented Oct. 6, 1914.

Application filed February 25, 1914. Serial No. 820,802.

To all whom it may concern:

Be it known that I, THOMAS J. FAY, a citizen of the United States, residing at Brooklyn, in the county of Kings and State 5 of New York, have invented a certain new and useful Improvement in Internal-Combustion Engines, of which the following is a full, clear, and exact description, reference being had to the accompanying drawings.

This invention relates to internal combustion engines of the kind which are provided with hollow reciprocating slide valves for controlling the inlet and the exhaust 15 respectively.

The object of the present invention, generally speaking, is to provide such improvements in the construction and arrangement of the valves of engines of the above kind 20 as shall render the valves more efficient in their action.

More limitedly, the invention consists of providing internal combustion engines with slide valves which are mounted between 25 wedge-shaped guide surfaces converging toward the cylinder while that part of each valve remote from the cylinder is subjected to lateral pressure at one or more points in its length, the pressure being produced 30 in any convenient manner, as by the application of springs, the arrangement being such that the application of pressure in this manner, combined with the co-acting wedge-shaped surfaces of the valves and guides, 35 effects a packing of the valves so that the leakage is in consequence prevented.

The invention also consists limitedly in providing superposed controlling ports in each valve with a partition above the upper 40 ports and a second partition below the lower ports, the effect of which is that at each charge a volume of fuel is admitted into the slide valves which volume for example, in a four-stroke cycle engine remains 45 inclosed in the inlet slide valve during all the phases of the cycle with the exception of the inlet or suction stroke, so that the inclosed volume of fuel assumes a homogeneous condition and absorbs heat,

for example, from the explosion gases; or 50 it may be specially heated in any suitable manner whereby the pressure and temperature at which the fuel is admitted into the cylinder is increased. Where oil is used as fuel, the advantage of this pre-heating 55 of the fuel will be all the more apparent. If, in such a construction of the controlling system as described, the gaseous mixture inclosed within the inlet slide valve explodes for any reason, then the compressive 60 forces produced thereby are transmitted, on account of the wedge shape of the valve, in such a manner that their resultant acts upon that part of the valve remote from the cylinder and against the load due to the 65 externally applied pressure, so that the slide valve is forced away from its packing surfaces, and any risk of bursting or breaking is thereby obviated.

The invention further consists limitedly 70 in the provision, between the ports in the slide valves and the ports in the cylinder walls, of symmetrically disposed chambers or passageways, so that the gases passing between the slide valve and the cylinder on 75 the inlet side and between the cylinder and the slide valve on the exhaust side are split up into two separate streams.

The invention still further consists limitedly in arranging the intermediate passageways in such a manner that, upon the inlet side the aforesaid chambers or passageways are divergent in the direction of the flow or gases while upon the outlet side they converge in the direction of the flow 85 of the gases, so that while the entering fluids have free access to the cylinder the exhaust gases issuing from the cylinder are throttled during their passage through the intermediate spaces or chambers.

The invention consists still further, limitedly, in so constructing the valves as to produce a valve possessing the advantages of a balanced valve in a construction where- 90 in the machining can be produced by an outside free stroke; also to produce a valve of the type referred to possessing marked advantages over other types of valves.

The invention still further and more generally consists in the details and combinations hereinafter more particularly referred to, included in the claims hereof, and illustrated in the accompanying drawings, wherein—

Figure 1 is a longitudinal sectional elevation showing an internal combustion engine constructed and arranged in accordance with the invention and provided with separate slide valves for the admission and for the exhaust; Fig. 2 illustrates in elevation and plan the slide valve for controlling the admission, while Fig. 3 is a similar view illustrating the exhaust controlling valve; and Figs. 4 and 5 are respectively sectional plans upon the lines 4—4 and 5—5 of Fig. 1.

In carrying the invention into effect in one convenient embodiment, there is provided the usual cylinder 1 in which the piston 2 of the engine is adapted to work, guideways or chests 3 and 4 being also provided for the slide valves 5 and 6 respectively, whereof the slide valve 5 controls the admission while the slide valve 6 controls the exhaust. The guideways or chests 3 and 4 are provided with inclined or wedge-shaped side walls converging toward the cylinder wall and the guideways are preferably further arranged in such a manner that they are diametrically opposite one another with respect to the cylinder, so that a symmetrical arrangement results.

The slide valves 5 and 6 are formed with inclined side walls having an inclination corresponding with that of their respective guideways, while the part 7 of each valve which is remote from the cylinder is exposed at its outer side to atmospheric pressure and is further subjected to pressure at two points in its length, the pressure being produced in the case of the modification illustrated in Figs. 1 to 5 by means of the springs 8 arranged within the housings 8^a and pressing against the shoes 8^b.

Each slide valve is provided with superposed controlling ports 12 and 14 and above the upper controlling ports 12 is formed in any suitable manner a wall or partition 13 while a similar wall or partition 15 is located below the lower controlling ports 14. In the case of the exhaust valve 6, it is preferred to make the lower controlling ports 14 of a greater length than that of the upper ports 12. The arrangement is such that, while the two valves are substantially symmetrical, each having a chamber therein with longitudinally spaced ports, the lower ports of the exhaust valve will be in communication with the exhaust outlet conduit at all times, insuring a free delivery of the exhaust gases introduced thereinto through the upper ports. On the other hand, the

length and arrangement of the ports in the inlet valve is such that the charge of the gaseous fuel is trapped within the chamber during three strokes of the working piston except the suction stroke, at which time the lower ports are in communication with the supply conduit whereby, if any working fluid additional to the charge contained within the valve is required, this additional fluid may enter the valve chamber and pass directly into the cylinder, thus assuring a cylinder full of mixture, even though the amount of mixture contained within the valve chamber may be insufficient to fill the cylinder. This will be evident from an inspection of Fig. 1, wherein the inlet valve is shown in the position which it occupies during the suction stroke of the piston 2. Because of this treatment, the gaseous charge is admitted to the cylinder at an increased temperature and pressure. The advantages of treating heavy hydro-carbon fuel in this manner will be obvious.

If the charge of fuel should for any reason explode within the slide valves, the compressive forces are transmitted in such a manner, due to the wedge shape of the valves, that the resultant pressure acts upon the part 7 of each valve, forcing the latter, against the external yielding pressure, away from its seating so that all risk of the bursting or breaking of the cylinder or slide valve will be obviated.

The controlling ports 12 and 14 and the corresponding cylinder ports 17 are located in the inclined surfaces of the valves and valve casings or guideways so that symmetrical spaces or chambers 19 are formed between the cylinder wall and the controlling ports on the admission side, while similar spaces or chambers 20 are provided on the exhaust or outlet side, which spaces cause the entering and issuing fluids to break up into two symmetrical streams.

For the purpose of increasing the efficiency of working, it is preferred to arrange the spaces 19 so that the area increases in the direction of the flow of the entering fluids while, in the case of the chambers 20, the area decreases in the direction of the flow of the exhaust gases, so that in the one case free entry of the charge into the cylinder is permitted while in the case of the exhaust gases these are throttled during their passage through the chambers or spaces 20.

The shape of the chambers or passageways 20 is such that the exhaust gases will flow at substantially constant speed from the cylinder ports into the valve ports, this constancy of speed being maintained independently of the pressure. This maintains the integrity of the escaping gases and enables them to maintain a plug-like characteristic

until beyond the combustion chamber. Because of maintaining this plug-like character, a partial vacuum is created within the spaces through which they pass and because 5 this plug-like form is maintained until after the gases pass the combustion chamber, the gases are prevented from flowing back into the combustion space or chamber, notwithstanding the partial vacuum created therein.

10 The action in maintaining the constant speed in the exhaust gases is analogous to that which is secured through a Venturi tube or a modification of the same. By having the ports 14 and the exhaust valve in continuous 15 communication with the outlet connection, the exhaust is permitted to flow into the outlet connection before it has an opportunity to cool and consequently to be discharged through the exhaust valve without loss of 20 speed. This construction of the exhaust valve coöperates with the construction of the passageways 20 to preserve the plug-like character in the exhaust gases referred to above.

25 The valve construction disclosed herein is particularly advantageous in a structural way, in that the wedge-shaped guideways are open on the exterior, thus permitting of the machining of the guide faces through 30 this open cut.

It will be observed that, on account of the acuteness of the angle between the convergent faces of each guideway, the gaseous pressure effective to push the wedge-shaped 35 valves from their seats is trifling. The gaseous pressure is applied to the valves through the ports within the guideway walls. Owing to the acuteness of the angle formed between the convergent faces of each guideway, 40 the resultant pressure which is available to force the valves out of their seats in these guideways is reduced to a minimum and is overbalanced by the superior pressure or leverage on the outer face of the valve, 45 applicable through the ports 11 or the springs 8. By properly relating the angles of the side walls of the valves to the yielding pressure exerted on the outer face, a construction is produced which approximates 50 that of a balanced valve; and this construction permits the machining of the parts to be accomplished by an outside and free stroke. While any angle between the tapering side walls of a valve and between 55 the tapering side walls of the corresponding guideway will suffice that will afford a superior pressure on the outer surface of the valve (from the same source) than is exercised in opposition thereto through the inclined surfaces, a convenient angle for this 60 purpose and one which permits of machining is an angle of 30° between the side walls, or an angle of 15° for each side wall.

It is to be understood that the invention

is not to be confined to the particular details 65 of construction or arrangement of the various parts relatively to one another hereinbefore described, as these and other details may be suitably modified, depending upon the particular practical requirements that 70 the invention is designed to meet.

Having thus described my invention, what I claim is:—

1. In an internal combustion engine, the combination of a cylinder having a port; a 75 tapered or wedge shaped guideway having surfaces converging toward the cylinder and being open at the side remote from the cylinder, a hollow tapered or wedge shaped valve slidably mounted in said guideway 80 and provided with a chamber having a port arranged to communicate with the cylinder port, a cover for the outer or enlarged end of the guideway, said cover being spaced from the adjacent surface of the valve, and 85 yieldable means interposed between the cover and the valve and operating to press the valve within its seat in the guideway.

2. In an internal combustion engine, the combination of a cylinder having a pair of 90 laterally spaced ports, a tapered or wedge shaped guideway extending longitudinally of the cylinder and interposed between said ports, said guideway being open at the side remote from the cylinder and having a port 95 in each of its convergent walls adapted to communicate with the correspondingly located cylinder port, a hollow tapered or wedge shaped valve slidably mounted in the guideway and provided with ports arranged 100 to register with the guideway ports, a cover for the open end of the guideway, said cover being spaced from the valve, and springs interposed between said cover and said valve.

3. In an internal combustion engine, the combination of a cylinder having a port, a tapered or wedge shaped guideway having surfaces converging toward the cylinder and being open at the side remote from the cylinder and having a port in each side wall thereto, a hollow tapered or wedge shaped valve slidably mounted in said guideway and having ports arranged to communicate with the guideway ports, and a cover for the outer or enlarged end of the guideway and spaced from the outer wall of the valve, there being means between the cover and the valve whereby the pressure exerted upon the converging side walls of the valve through 110 the guideway ports may be coöperatively opposed.

4. In an internal combustion engine, the combination of a cylinder having a port, a tapered or wedge shaped guideway having 115 surfaces converging toward the cylinder and forming with each other an acute angle, a hollow tapered or wedge shaped valve slid-

ably mounted in said guideway and adapted to communicate with the cylinder port, a cover for the outer or enlarged end of the guideway, said cover being spaced from the adjacent surface of the valve, the space between the convergent faces of the guideway being arranged to communicate with the cylinder, and there being means interposed between the cover and the valve whereby the

pressure thus exerted to unseat the valve 10 may be coöperatively opposed.

In testimony whereof, I hereunto affix my signature in the presence of two witnesses.
